UNITED STATES PATENT OFFICE.

LEVI J. ROY, OF PROVIDENCE, RHODE ISLAND.

DESIGN FOR A CLASP.

Application filed January 27, 1923. Serial No. 5,015. Term of patent 3½ years.

To all whom it may concern:

Be it known that I, LEVI J. ROY, a citizen of the United States, residing at Providence, in the county of Providence and State of Rhode Island, have invented a new, original, and ornamental Design for a Clasp, of which the following is a specification, reference being had to the accompanying drawings, forming part thereof.

Figure 1 is an obverse view of the clasp;
Figure 2 is a reverse view of the clasp and

Figure 3 is an edge view of the clasp.
I claim:

The ornamental design for a clasp, as shown.

In testimony whereof I have signed my name to this specification in the presence of two subscribing witnesses.

LEVI J. ROY.

Witnesses:

S. N. BARRY,
J. A. MILLER.
